UNITED STATES PATENT OFFICE.

HOWARD M. NICHOLSON, OF PITTSBURGH, PENNSYLVANIA, ASSIGNOR OF ONE-FOURTH TO GEORGE B. NICHOLSON, ONE-FOURTH TO ARTHUR D. NICHOLSON, AND ONE-FOURTH TO WILLIAM T. LOWERY, ALL OF PITTSBURGH, PENNSYLVANIA.

AUTOMATIC DISPENSING APPARATUS.

1,327,111.

Specification of Letters Patent.

Patented Jan. 6, 1920.

Application filed March 28, 1918, Serial No. 225,195. Renewed June 16, 1919. Serial No. 304,739.

To all whom it may concern:

Be it known that I, HOWARD M. NICHOLSON, a citizen of the United States of America, residing at Pittsburgh, in the county of 5 Allegheny and State of Pennsylvania, have invented certain new and useful Improvements in Automatic Dispensing Apparatus, of which the following is a specification.

This invention relates to dispensing apparatus and it has for its object to provide an improved device for dispensing fuel or lubricating oil for the use of motorists.

The advantages of the present invention will be further appreciated if existing conditions in the art are clearly understood. Because of the strict fire regulations in some cities it is not permissible to place the main containing tanks of gasoline or other volatile and explosive oils under air pressure. 10 The employment of pumps for forcing the oil to be dispensed, to the point of outlet, is expensive and annoying because, when the pumps are power operated the cost of the power for operating them is considerable and, in addition, these pumps frequently get out of order, often at a time when the garage is the busiest in dispensing gasoline.

As this description proceeds it will be seen 15 that the present invention utilizes the ordinary city water supply in conjunction with a novel type of vacuum creating means, to create a vacuum in a transparent container, so that the gasoline will be drawn into said container where it will be visible to the owner or driver of the automobile to be supplied, so that the purchaser will be assured that he is getting full measure. It will also be seen that the apparatus is practically automatic in its operation, it being only necessary for the operator to manipulate the proper valve or valves in order to quickly and accurately dispense any desired quantity of gasoline or lubricating oil.

20 A further important feature of the invention resides in the fact that the parts are so correlated and arranged that the vacuum creating means may undergo a preparatory operation during the time that the gasoline is being discharged from the container into a waiting car, thus setting the apparatus in condition to repeat the dispensing operation for a succeeding car as soon as the first car

has been supplied. Still another object of the invention is to provide a vacuum creating means of the type above set forth adapted to be automatically controlled from a distant point so that the container and dispenser may be located at the curb line, while the vacuum creating means may be located 55 within the garage or other building, where it will be safe from freezing and secure against being tampered with by unauthorized persons.

Further objects and advantages of the invention will be set forth in the detailed description which now follows:

In the accompanying drawing:

Figure 1 is a diagrammatic view of an apparatus constructed in accordance with the 60 invention.

Fig. 2 is a detailed view of the controlling means of the cocks in the water supply and waste line and

Fig. 3, is a detail view of the drain back 65 mechanism employed in the dispensing container.

Like numerals designate corresponding parts in the drawing.

The apparatus comprising the present invention consists of a water tank 5 having a waste pipe 6 leading from the bottom thereof. Any suitable water seal may be provided in the length of this waste pipe, such for example as the box 7 and overflow pipe 8. 75 9 designates a water supply line from a city service main, this line delivering into the bottom of the tank 5. Cocks 10 and 11 are disposed in the pipes 9 and 6 respectively and the ports thereof are so disposed 80 that when the cock 10 is closed the cock 11 is open and vice versa. The plugs 12 and 13 of these cocks are provided with operating cranks 14 and 15 and these cranks are connected by links 16 and 17 to a stem 18. 85 This stem is carried by a diaphragm 19 and projects through the top of a diaphragm casing 20. A spring 21 is disposed between the diaphragm 19 and the bottom 22 of the diaphragm casing and normally tends to 90 move the diaphragm upwardly. A pipe 23 leads from the top of the tank 5 to the lower portion of a transparent container 24, the latter being mounted upon a pedestal 25, adapted to support the container 24 at the curb 95 line and in such position that a discharge

hose 26 from the container may be placed directly in the tank of a waiting automobile. The container 24 is graduated to indicate gallons and a valve 27 controls the 5 passage of gasolene from the container to the hose 26. A pipe 28 leads from the pipe 23 through the bottom of the diaphragm casing 20 and is in communication with the space beneath the diaphragm 19. When the 10 diaphragm 19 is in its raised position under the action of spring 21, the cock 10 is closed and the cock 11 is open; and when the diaphragm 19 is drawn downwardly against the action of spring 21 by the creation of 15 vacuum beneath the diaphragm, the cock 10 will be opened and the cock 11 will be closed. A valve 29 is disposed in, and controls the passage of pressure fluid through pipe 28, while a valve 30 is disposed in, and controls 20 the passage of pressure fluid through pipe 23. An air valve 31 is adapted to admit atmosphere to the interior of the container 24 as will be hereinafter set forth.

While I have illustrated a plurality of 25 independent valves 29, 30 and 31, to perform the several desired functions this is primarily for the purpose of making the drawing clear and facilitating the understanding of the operation of the device, it being understood that it would be well within the 30 range of mechanical skill and a mere adaptation of any well known multiple way valve upon the market to utilize a four way valve in the carrying out of these several 35 functions.

An outwardly opening check valve 32 permits the escape of air from the top of tank 5 as the water rises therein and a float operated check valve 33, which closes when the 40 water reaches the top of tank 5, prevents the entry of water to the pipe 23.

The apparatus having been installed it is necessary to operate it the first time by hand, to which end the operator presses downwardly upon the stem 18, to force the diaphragm 19 downwardly against the action of the spring 21. This opens cock 10 and closes cock 11 and water from the service pipe 9 flows into the tank 5 and fills the 45 same, the air escaping through the air valve 32 at this time. As soon as the tank 5 has been filled the operator releases the stem 18 and the spring 21 raises the diaphragm thereby closing the cock 10 and opening the 50 cock 11. The water will thereupon start to run out of tank 5 thereby creating a vacuum in the top of said tank and creating a vacuum in pipe 23. The valve 29 being then opened a vacuum will be created beneath the 55 diaphragm 19 and this diaphragm will be drawn downwardly, thereby opening cock 10 and closing cock 11. The valve 29 is then closed and the parts will be held in the position stated, namely with the cock 10 open 60 and the cock 11 closed due to the fact that

with the valve 29 closed, no air can enter beneath the diaphragm 19 to break the vacuum. Thereupon the water will again rise in tank 5. The foregoing operation constitutes a preliminary setting of the mechanism prior 70 to the actual dispensing operation. When it is desired to dispense the gasolene, valve 29 is opened which results in the vacuum beneath the diaphragm 19 being broken, due to the fact that the rise of water in the 75 water tank changed the condition of vacuum to a condition of pressure in said tank with the result that the diaphragm will rise closing cock 10 and opening cock 11. Thereupon the water in tank 5 will start to fall 80 and will tend to create a vacuum in the upper portion of said tank which will result in drawing gasolene into the container 24, (whenever valve 30 is opened) through a supply pipe 35 which extends upwardly 85 from a gasolene supply tank 36 that is preferably located beneath the ground. The flow of gasolene into the container 24 may be instantly stopped by closing the valve 30. After the desired amount of gasolene has 90 been drawn into the container 24 the valve 30 is closed, the hose 26 is properly adjusted, the valve 27 is opened and then the air valve 31 is opened to permit air to pass to the interior of the receptacle. The closing of the valve 30 causes the full strength of the 95 vacuum (part of which had previously been directed to drawing gasolene into container 24) to be exerted upon the underside of the diaphragm 19 and results in drawing this 100 diaphragm downwardly against the action of the spring with the result that the cock 10 is again opened and the cock 11 closed and the tank 5 refills, preparatory to repeating the operation, it being thus seen that the 105 time during which the gasolene is passing from the container 24 through the hose 26 to the tank of a waiting automobile, is utilized in filling the tank 5 so that when another automobile moves into position the apparatus will be in condition to immediately 110 repeat the operation above set forth.

It is to be noted that the tank 5 is entirely free of internal mechanism and the structure as a whole comprises but a few, simple 115 and inexpensive parts. The operation of the cocks 10 and 11 may be controlled by the diaphragm from a distant point. In other words, these cocks may be actuated to secure the desired results by the manipulation of 120 valves located at the container or in other words located at the curb line where the garage man will be stationed. This renders it possible to put the tank and associated parts inside of the garage where there will 125 be no danger of the water freezing in cold weather and where there will be no possibility of the apparatus being tampered with by dishonest or mischievous persons. It will further be seen that the connections be- 130

tween the tank 5 and associated parts and the container will consist of the comparatively small and inexpensive pipes 23 and 28; thus the container may be located at any 5 desired distance from the tank 5 at but a small cost.

In order to render it possible to determine, at any time how much gasoline has been dispensed through the apparatus, I 10 locate within the container 24, a meter or counter 37 that is actuated by a float carrying rod 38. A check valve 39 is disposed in pipe 35 and prevents the contents of the receptacle from passing back into the tank 36. 15 To insure accurate measurement of the commodity dispensed, I provide a plurality of pipes 40 of varying heights which project vertically into the container 24. The lower ends of these pipes lead to a valve 20 casing 41, within which a plug 42 is mounted to turn. This plug carries a handle 43 and this handle carries a pointer 44 which co-acts with indicating marks (not shown) formed upon an end 45 of the casing 41. 25 The casing 41 is provided with a longitudinally extending groove 42^a and the end of the casing 41 opens into the pipe 35 below the check valve 39. The plug 42 is provided with a plurality of ports 46 all of which 30 communicate with the groove 42^a, these ports being adapted to severally register with corresponding ones of the pipes 40.

If, for example, it be desired to dispense four gallons of oil, the operator will leave 35 the valve 30 open long enough to draw gasoline into the container 24 to a point slightly above the next to the longest of the pipes 40. The handle 43 will then be turned until it registers with that mark on end 45 indicative 40 of 4 gallons, whereupon the contents of the container 24 will drain out through said next to the longest pipe 40 into groove 43 and thence through pipe 35 to the main tank 36.

45 Having described my invention what I claim is;

1. In combination, a measuring container, a supply pipe leading thereto, a water tank, supply and waste pipes for the water tank, 50 valves located in the supply and waste pipes, and pressure actuated means operable by pressure created by the movement of the water in the water tank for actuating said

valves, and a connection between the tank and the container. 55

2. In combination a water tank, supply and waste pipes for the water tank, valves located in the supply and waste pipes, pressure actuated means operable by pressure created by the movement of the water in the water tank, and connections between the pressure actuated means and the valves, whereby movement of said pressure actuated means in one direction opens one of said valves and closes the other and vice versa. 60 65

3. In combination a water tank, supply and waste pipes for the water tank, valves located in the supply and waste pipes, a diaphragm, a connection between the tank and said diaphragm, and connections between the diaphragm and the valves, the movement of the diaphragm in one direction opening one of said valves and closing the other and vice versa. 70

4. In combination, a measuring container, 75 a supply pipe leading thereto, a water tank, supply and waste pipes for the water tank, valves located in the supply and waste pipes, a pressure actuated means controlling the said valves, a connection between the tank 80 and the container, and a second connection between the first named connection and the pressure actuated means.

5. In a device of the character described, the combination with a dispensing container, 85 of a source of oil supply leading thereto, a plurality of pipes of varying heights opening into the container, a connection which leads to the source of oil supply and means for successively bringing said pipes into 90 communication with said connection so that oil may drain from the container back to the source of oil supply according to which of said pipes is brought into communication with the connection. 95

6. In a device of the character described the combination with a source of oil supply, a dispensing receptacle, a plurality of pipes projecting into said receptacle, said pipes being open at the top and being of various 100 heights, and a common controlling valve for all of said pipes adapted to establish communication between any one of said pipes and the source of supply.

In testimony whereof I affix my signature. 105
HOWARD M. NICHOLSON.
